CLAIM

The ornamental design for a jewelry pendant, as shown and described.

DESCRIPTION

FIG. 1 is a front top perspective view of a jewelry pendant showing our new design.

FIG. 2 is a rear bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front top perspective view of a further embodiment of a jewelry pendant showing our new design.

FIG. 10 is a rear bottom perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof; and,

FIG. 16 is a bottom plan view thereof.

The broken lines shown illustrate portions of the jewelry pendant and form no part of the claimed design.

1 Claim, 12 Drawing Sheets
